UNITED STATES PATENT OFFICE.

PETER S. LAMB, OF OTTAWA, ONTARIO, CANADA.

TAMPING-MACHINE.

1,282,879.

Specification of Letters Patent. Patented Oct. 29, 1918.

Application filed March 19, 1917. Serial No. 155,829.

To all whom it may concern:

Be it known that I, PETER S. LAMB, a citizen of the Dominion of Canada, residing at Ottawa, in the county of Carleton and 5 Province of Ontario, Canada, have invented certain new and useful Improvements in Tamping-Machines, of which the following is a specification.

This invention relates to tamping machines which are most commonly used in connection with the opening up and filling of drains. It consists of a frame-work mounted on two pairs of wheels, and an oscillatory carriage having a tamping means 10 at its outer end which can be swung the width of the drain. I provide a changeable foot so that the machine can be used in breaking concrete, hard earth or drilling rock while opening up a drain. 15 20 With these and other objects in view, the invention consists in the construction, combination and arrangement of parts as will be hereinafter fully described, illustrated in the accompanying drawing, and pointed out 25 in the claims hereunto appended.

Figure 1 show a perspective view of my invention. Fig. 2 shows a top plan view of the supporting carriage. Fig. 3 shows a top plan view of the reciprocating carriage. 30 Fig. 4 shows an elevation at the rear. Fig. 5 shows a front elevation, part broken away. Fig. 6 shows a section of the driving wheel. Fig. 7 shows a sectional view of the journal bearing for the driving wheel. Fig. 8 shows 35 a top plan view of the tamping foot. Fig. 9 shows a section view on line 9—9 of Fig. 8. Fig. 10 shows a section view on line 10—10 of Fig. 8. Fig. 11 shows the tamper and an operating cylinder.

40 Referring to the drawings like numerals designate like parts in the various drawings. 20 indicates a pair of steering wheels and 21 indicates a pair of driving wheels. These wheels are mounted on suitable axles 22 on 45 which is supported a suitable frame-work 23. The frame-work 23 can be raised or lowered by means of the set-nuts 24 so that when the machine is sitting on uneven ground one wheel may be considerably lower 50 or higher than the other wheels, thus leaving the frame-work 23 in a level position. The perpendicular portion of the axle 22 of the steering wheels 20, is provided with arms 24^a which are joined together at their outer

end by a cross-bar 25. 26 is a lever having 55 its inner end hingedly connected to the frame-work 23 and the outer end extending back beyond said frame-work. A connecting member 27 connects said lever to one end of member 25. It is by this lever 26 that 60 the machine is steered. I provide a notched plate 28 to be securely mounted on one of the cross-bars of the frame-work 23, so that the lever 26 may be swung into any of these notches, thus setting the rear or 65 steering wheels at the desired angle. The cross-bar 25 has a U-shaped member 29 extending downwardly near its center. This U-shaped member is provided to hold a short tongue 30, which has its inner end hingedly 70 connected to one of the cross members of the frame-work 23. The outer end extends out considerably past the rear end of the frame-work 23 and is provided with any suitable clamping means so that it can be attached to the rear of a wagon for hauling from place to place. When it is desired to use the tongue 30 for steering, the connecting member 27 is released at its outer end from the end of cross-bar 25. 75

The driving wheels 21 are provided with a suitable sprocket wheel 31 on their inner side. Attached to the outer end of the shaft 22 of the drive wheels, I provide braces 32 which extend back and are attached to an 80 extending end of one of the cross-bars of the frame-work 23. By having these braces 32 the drive wheels 21 will always be kept in parallel alinement with the sides of the main frame 23. 85

33 indicates the oscillatory frame which is pivotally mounted at 34 to the frame-work 23. This frame-work is provided with a suitable power driving means 35 which may be a gasoline engine, motor or any other arrangement desired. 36 is a perpendicular pin having a beveled gear 37 at its upper end and a beveled gear wheel 38 at its lower end. 39 is a cross shaft having its ends journaled in the bearings 40. This cross 100 shaft 39 carries a gear wheel 41, a smaller wheel 42, a forward drive beveled gear wheel 43, a reverse drive beveled gear wheel 44 and a slidable clutch 45, the ends of which are provided with suitable gears 105 so as to engage with suitable gears on the inner side of gear wheels 43 and 44. 46 is a lever attached at one end to the slidable

clutch 45 and the other end extends to the rear of the frame-work 23. 47 is a cross shaft behind and parallel to the cross-shaft 39. This shaft carries a drive wheel 48 at 5 one end, a gear wheel 49 adapted to mesh with the gear wheel 41, a larger gear 50 adapted to mesh with gear wheel 42, clutches 51 adapted to slidably engage with either gears 49 or 50. 52 is a lever, one end extending behind the frame-work 23 and the other end being bifurcated and attached to the clutches 51. 53 is a belt running from the drive wheel 48 to the drive wheel of the power means. It will be seen that the shaft 15 47 and the shaft 39 are constantly turning. In the usual rate of tamping or of opening a drain the machine is moving at low speed, that is, the gear 49 is driving the gear 41. If high speed is required operate the handle 52 so as to make the gear 50 turn the gear 20 42 in the same direction that the gear 41 was turned.

54 is the main drive shaft journaled in the frame-work 23 and carrying thereon a 25 sprocket wheel 55, a brake wheel 56 and at its ends sprocket wheels 57. 58 is a shaft journaled in the frame-work 23 and carries a beveled gear wheel 59 adapted to mesh with beveled gear wheel 38, and at one end 30 a sprocket wheel 60 in alinement with sprocket wheel 55. Sprocket chain 61 connects sprocket wheels 55 and 60. Sprocket chains 62 connect sprocket wheels 31 and 57. 63 is a brake connected to a brake band 35 64 which extends around the brake wheels 56. This brake can be used when the machine is going up or down hill.

Canadian Patent 145,946 granted to Raleigh H. Staley, on February 11, 1913, 40 covers a tamping machine which operates the tamper in the manner as shown in the inclosed drawing and thus I do not wish to claim anything on the particular means of raising and lowering the tamper. I improve 45 the construction as shown in the said patent by having the lever 65 operate both the tamper holding clutches 66 and the drive clutch 67 at the one time, thus eliminating the possible mistake of starting the drive 50 wheel before the tamper holding clutches 66 are released. It has been found in operation that the smooth face of the segment 68 slips on the side of the upright tamper and I improve this as shown in Fig. 11. 55 The tamper 69 is provided with the toothed member 70 which is countersunk in its side while the segment has a corresponding toothed member 71 on its face. The operating of the tamper will now be more accurate 60 and no slipping will occur.

Referring to the foot 72 I provide a foot having a hollow center 73 adapted to receive the spiked tooth 74 which will be used in breaking cement, pavements, earth, or drilling 65 in rock. When the machine is used in

tamping earth in a drain the dummy tooth 75 is used. 76 is a set of braces which aid considerably in strengthening the foot.

At the rear of the frame-work 23 I provide a hingedly connected step 77, this will 70 be found of great convenience, as the operator can stand on this step while the wheels straddle the drain and from this position he has full control over the various levers which all extend back toward this end. 78 75 is a tool box which can be mounted on the frame-work 23 in any desirable position.

When desirous of going around a very short corner it will be found to great advantage to draw the pin 79 on the inner side 80 of the turn so that the sprocket wheel 57 which has the pin withdrawn will be free on the shaft 54. By doing this power will be given to the outside drive wheel and it will turn quicker than if power were on 85 both wheels.

From the foregoing it is thought that the construction of my invention will be clearly understood, and therefore a more extended explanation has been omitted. 90

What I claim as new is:—

1. A machine of the class described, comprising a vertically slidable tamper, a pivoted carriage, a traction framework on which said carriage is pivotally mounted, 95 operating means for said tamper, holding clutches, and a drive clutch and means whereby said clutches are operated at one and the same time, thus eliminating possibility of starting the drive wheel before the 100 holding clutches are released.

2. A machine of the class described, comprising a vertically slidable tamper, a pivoted carriage, a traction framework on which said carriage is pivotally mounted, 105 operating means for said tamper, holding clutches, a drive clutch and means whereby said clutches are operated at one and the same time, thus eliminating possibility of starting the drive wheel before the holding 110 clutches are released, said tamper being provided with a countersunk toothed member for co-operation with a toothed segment for preventing slipping of the tamper.

3. A machine of the class described, comprising a vertically slidable tamper, a pivoted carriage, a traction framework on which said carriage is pivotally mounted, operating means for said tamper, holding clutches, and a drive clutch and means 115 whereby said clutches are operated at one and the same time, thus eliminating possibility of starting the drive wheel before the holding clutches are released, the tamper being provided with a toothed member, and 120 a co-operating toothed segment.

4. In a machine of the class described, the combination of a vertically slidable tamper, operating means for said tamper, dogs adapted to hold said tamper in a raised position, 130

tion, a drive wheel adapted to receive transmission for said tamper from said operating means, and a lever adapted to disengage said dogs and engage the driving clutch 5 with said drive wheel simultaneously.

5. In a machine of the character described, the combination of a main frame supported on two pair of wheels, a pivoted carriage mounted between the two front wheels to 10 swing the width of the ditch, a power drive mechanism positioned on one end of said carriage and a vertically slidable tamper with operating means therefor positioned at the opposite end of said carriage so as to 15 constitute a counterbalance at the ends of said carriage, tamper holding means, means for simultaneously controlling the same and the tamper operating means.

6. A machine of the character described, 20 the combination of a main frame, a pivoted carriage mounted on said main frame, a tamper and operating means at one end of

said carriage, and a power driving mechanism at the other end of said carriage, tamper holding means, a lever for simultaneously actuating the same and controlling the tamper actuating means, a traction mechanism mounted on said carriage, connecting means so as to operate the front 25 pair of said wheels.

7. A machine of the character described comprising a main frame, a pivoted carriage mounted on said main frame, tamping means at one end of said carriage, tamper-actuating means, tamper-holding means, 30 and a lever for simultaneously actuating the same and controlling the tamper-actuating means.

In testimony whereof I affix my signature in the presence of two witnesses.

PETER S. LAMB.
